FIG. 6.

M. B. Carter Inventor

By *Frank Murphy Jr.* Attorney

UNITED STATES PATENT OFFICE.

MOSCOW B. CARTER, OF FRANKLIN, TENNESSEE.

BITE METER.

Application filed January 6, 1927. Serial No. 159,427.

This invention has for one of its objects to render it unnecessary for a dentist to resort to guess work in selecting artificial teeth of a length similar to the natural teeth that they 5 are to replace, and to attain this end comprehends the provision of a novel, simple and inexpensive instrument through the medium of which the length of the natural teeth may be readily ascertained before their extraction.

With the foregoing and other objects in view the invention consists of the construction, combination and arrangement of parts hereinafter fully described and claimed, and illustrated in the accompanying drawing, 15 wherein:

Figure 1 is a view in front elevation of the instrument,

Figure 2 is a view in side elevation of the instrument,

Figure 3 is a rear view of a fragmentary portion of the instrument,

Figure 4 is a sectional view taken on the plane indicated by the line 4—4 of Figure 1,

Figure 5 is a similar view taken on the 25 plane indicated by the line 5—5 of Figure 1, and

Figure 6 is a perspective view of the adjustable blade and slide of the instrument.

The instrument comprises a standard 1, a 30 blade 2 fixed to the upper end of the standard, and a blade 3 adjustable on the standard. The standard 1 is divided into millimeters commencing at the blade 2. The blades 2 and 3 extend in opposite directions from the standard 1. The blade 3 is carried by a slide 4 which is of the split resilient type and has sufficient frictional contact with the standard 1 to prevent its casual movement thereon. The blade 3 is secured to the 35 slide 4 through the medium of arms 5 which extend at right angles thereto and are soldered or welded to the slide.

The instrument, which is termed a bite meter, is adapted to be used for the purpose of ascertaining the normal bite, the high lip 45 line, and the low lip line of a patient. To ascertain the normal bite, which is done by measuring the distance between the under side of the chin and the nose with the teeth closed, the blade 2 is pressed firmly against 50 the under side of the nose and the blade 3 is adjusted on the standard 1 until it is in snug contact with the under side of the chin. The high lip line is ascertained by measuring the distance from the cutting edges of the 55 upper front teeth to the nose, and in measuring this distance the blade 2 is pressed firmly against the under side of the nose and the blade 3 is adjusted on the standard 1 until it is in contact with the cutting edges of said 60 teeth. The distance between the cutting edges of the lower front teeth and the under side of the chin is measured in order to ascertain the low lip line, and this is done, after first reversing the blade 3 on the standard 1 65 so that it will project therefrom in the direction of the projection of the blade 2, by placing the blade 2 in contact with the cutting edges of said teeth and adjusting the blade 3 on the standard until it is in firm contact 70 with the under side of the chin. From the measurements thus obtained, the dentist will experience no difficulty in selecting artificial teeth normal as to length.

What is claimed is:—

A bite meter comprising a graduated standard, a fixed blade extending from an end of the standard, a resilient split sleeve 75 adjustably mounted on the standard, and a blade provided with arms arranged at right 80 angles thereto and secured to the slide.

In testimony whereof I affix my signature.

MOSCOW B. CARTER.
